(57) **CLAIM**

The ornamental design for an information handling system housing and support stand, as shown and described.

DESCRIPTION

FIG. 1 is a vertical orientation front perspective view of the information handling system housing and support stand comprising the present invention;

FIG. 2 is a vertical orientation front view thereof;

FIG. 3 is a vertical orientation left side view thereof;

FIG. 4 is a vertical orientation back view thereof;

FIG. 5 is a vertical orientation top plan view thereof;

FIG. 6 is a vertical orientation bottom plan view thereof;

FIG. 7 is a horizontal orientation front perspective view thereof;

FIG. 8 is a horizontal orientation front view thereof;

FIG. 9 is a horizontal orientation left side view thereof;

FIG. 10 is a horizontal orientation back view thereof;

FIG. 11 is a horizontal orientation top plan view thereof; and,

FIG. 12 is a horizontal orientation bottom plan view thereof.

Broken lines shown in the drawings illustrate portions of the information handling system housing and support stand, and form no part of the claimed design.
